UNITED STATES PATENT OFFICE

2,328,094

BOAT PLATFORM FOR VESSELS

Albert C. Perry, Toledo, Ohio

Application May 10, 1943, Serial No. 486,366

6 Claims. (Cl. 9—22)

This invention aims to provide a novel platform, and novel means for pivotally mounting it, preferably on the boat deck of a vessel, the construction being such that a boat, when supported on the boat deck, will hold the platform in a substantially horizontal position, outboard of the boat, the platform then being of use in shipping stores in the boat, working on it, and promoting the conveniences of passengers or hands.

Another object of the invention is to provide novel means whereby as the davits are swung inwardly or outwardly, a proper operative connection between the boat and the platform will be brought about.

It is within the province of the disclosure to improve generally and to enhance the utility of devices of that type to which the present invention appertains.

With the above and other objects in view, which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

In the accompanying drawings:

Figure 1 shows an end elevation, a device constructed in accordance with the invention;

Figure 2 is a top plan;

Figure 3 is a section on the line 3—3 of Figure 2;

Figure 4 is a section on the line 4—4 of Figure 2;

Figure 5 is a top plan showing a modified construction, of use when the davits are of the kind that rotate on a vertical axis, rather than having an inboard and outboard swinging movement, bodily, as in Figure 1 of the drawings;

Figure 6 is an end elevation of the structure shown in Figure 5.

Referring, first, to the form shown in Figs. 1 to 4, the numeral 1 marks the hull of a vessel, the spar deck appearing at 2, and the rail at 3. The cabin is designated by the numeral 4 and the roof of it constitutes a boat deck 5 having an overhang 50.

Rigid davits 6 are supplied, and are pivotally mounted at 7, at their lower ends, on the spar deck 2, to swing inboard and outboard, in parallel, thwartship planes. The boat is marked by the numeral 8, the keel thereof appearing at 32, the boat being connected to the upper portion

of the davits 6 by hoisting and lowering mechanisms, such as blocks 9 and falls 10, the falls being belayed on cleats 11, carried by thwartship arms 12, having their outer ends pivoted at 14 to the davits 6, intermediate the ends thereof. The arms 12 form part of a conventional means for limiting the outward swinging movement of the davits 6, and are not concerned with the present invention.

Outwardly projecting brackets 15 are secured to the overhang 50 of the boat deck 5. A platform 16 is pivotally mounted at 17, intermediate its ends, on the brackets 15, to swing vertically. The construction of the platform 16, shown in the drawings, will be dealt with hereinafter, but changes in the depicted form of the platform may be made, without departing from the spirit of the invention.

Assuming that, in Fig. 2, the part of the vessel that is designated by the numeral 18 is disposed toward the bow, the platform 16 may be said to comprise a forward transverse beam 19, an after transverse beam 20, and an intermediate transverse beam 21. The pivot elements 17, which support the platform 16 for vertical tilting movement, are engaged in the beams 20, 21 and 19.

A fore and aft catwalk or tread 22 is secured rigidly to the outboard ends of the beams 19, 21 and 20. A guard rail structure 23 extends longitudinally of the outer edge of the tread 22 and along the ends thereof and is carried by the tread and by the beams 19, 20 and 21. On its inboard side, the guard rail 23 is open, to give access to the boat 8, when the boat is on the boat deck 5.

Loop-shaped housings or guards 24 are secured to the inner ends of the platform beams 20, 21 and 19. Screws 25 are threaded into the lower portions of the guards 24, and are supplied at their upper ends with any suitable manipulating means, such as hand wheels 26, above which the guards 24 extend. The lower ends of the screws 25 are adapted to rest on the boat deck 5, and constitute adjustable legs for disposing the platform 16 parallel to the boat deck.

A supporting strip 27 is secured to the platform beam 21 and extends lengthwise thereof, in spaced relation thereto. The strip 27 and the beam 21 carry axles 28, whereon anti-friction devices 29, such as wheels, are mounted to rotate. The screw-legs 25 prevent the wheels 29 from coming into contact with the boat deck 5. The wheels 29 are mounted to rotate on fore and aft axes, represented by the parts 28. The intermediate platform beam 21 is somewhat longer than the

fore and aft beams 19 and 20, respectively, in order to accommodate the line of wheels 29.

Saddles 30 rest on the boat deck 5, removably, and support the boat 8. The inner ends of the saddles 30 are spaced apart a little, as shown in Fig. 2, at 31, so that the keel 32 of the boat may come into contact with the beams 19-20-21. The construction is such that, when the boat 8 is in place on the saddles 30, as shown in Fig. 1, the lower edge of the keel 32 will engage the beams 20, 21 and 19, and, thus, the boat serves to hold the platform 16 in the horizontal position of Fig. 1, it being possible for persons to occupy the tread 22, for any useful purpose.

The inhaul tackle 51 for the davits 6 forms no part of the present invention, and may be constructed as desired. By means of the block and falls 9-10, the boat is raised, and since the platform 16 is freed the weight of the boat, the platform swings outboard. When the davits 6 are swung outwardly, the boat 8 is carried outwardly for lowering away. The pivot elements 17 are easily removable, to permit the platform 16 to be hauled inboard, so as not to foul other vessels, docks, etc., in close quarters.

When the davits 6 and the boat 8 are swung outboard or inboard, the wheels 29 prevent an objectionable rubbing contact between the hull of the boat and the beams 21 of the platform 16, the beams 20 and 19 having contact with the keel 32 only.

In Figs. 5 and 6, parts hereinbefore described have been designated by numerals already used, with the suffix *a*. In this form of the invention, overhanging davits 33 are employed, in the place of the straight davits 6, the standards of the davits being mounted in any conventional way, at 34, on the spar deck 2a, or elsewhere, to rotate about vertical axes. The fore and aft thwartship beams 19a and 20a of the platform 16a, respectively, do not overhang the boat deck 5a, as do the beams 19 and 20 of Fig. 2, but have their inner ends pivotally connected to the edge of the boat deck 5a, by means of the brackets 15a, or otherwise.

The intermediate beam 21a of the platform 16a overhangs the boat deck 5a and carries a thwartship, elongated roller 35, journaled at 36 on the beam 21a and extended longitudinally thereof. The roller 35 replaces the wheels 29 of Fig. 5, and may be found more convenient than those wheels, since, when the davits 33 are employed, the boat 8a has to have a fore and aft movement in getting it outboard or inboard. Diagonal braces 38 have their inner ends secured to the intermediate beam 21a, the outer ends of the braces being secured to the platform beams 20a and 19a.

The operation of the device shown in Figs. 5 and 6 does not differ materially from the operation of the device shown in the remaining figures, saving insofar as the handling of the boat 8a may be concerned.

Having thus described the invention, what is claimed is:

1. In a device for rendering the outboard side of a boat accessible when the boat is in inboard position on a vessel, a platform, means for pivotally assembling the platform, intermediate its inboard and outboard edges, with the vessel, for vertical swinging movement, and means for lowering the boat until it rests on the inner portion of the platform, thereby to hold the platform in approximately horizontal position, with the outboard portion of the platform disposed outboard

of the boat, and in accessible relation thereto, and for raising the boat to cause the outboard portion of the platform to swing downwardly as the boat is carried outwardly.

5 2. In a device for rendering the outboard side of a boat accessible when the boat is in inboard position on a vessel, a platform, means for pivotally assembling the platform, intermediate its inboard and outboard edges, with the vessel, for vertical swinging movement, means for lowering the boat until it rests on the inner portion of the platform, thereby to hold the platform in approximately horizontal position, with the outboard portion of the platform disposed outboard of the boat, and in accessible relation thereto, and for raising the boat to cause the outboard portion of the platform to swing downwardly as the boat is carried outwardly, and anti-friction devices on the platform and positioned for contact with the boat when the boat is carried inboard or outboard.

10 3. In a device for rendering the outboard side of a boat accessible when the boat is in inboard position on a vessel, a platform, means for pivotally assembling the platform, intermediate its inboard and outboard edges, with the vessel, for vertical swinging movement, means for lowering the boat until it rests on the inner portion of the platform, thereby to hold the platform in approximately horizontal position, with the outboard portion of the platform disposed outboard of the boat, and in accessible relation thereto, and for raising the boat to cause the outboard portion of the platform to swing downwardly as the boat is carried outwardly, and a leg mounted for adjustment on the inner portion of the platform and engageable with a vessel, to level up the platform.

15 4. In a device for rendering the outboard side of a boat accessible when the boat is in inboard position on a vessel, a platform, means for pivotally assembling the platform, intermediate its inboard and outboard edges, with the vessel, for vertical swinging movement, means for lowering the boat until it rests on the inner portion of the platform, thereby to hold the platform in approximately horizontal position, with the outboard portion of the platform disposed outwardly of the boat, and in accessible relation thereto, and for raising the boat to cause the outboard portion of the platform to swing downwardly as the boat is carried outwardly, and a plurality of boat-engaging anti-friction devices mounted on the inner portion of the platform, for rotation about fore and aft axes.

20 5. A device for rendering the outboard side of a boat accessible when the boat is in inboard position on a vessel, constructed as set forth in claim 1, and wherein the raising and lowering means comprises a substantially straight davit having its lower end pivoted to the vessel for thwartship swinging movement, and block and falls tackle assembled with the upper portion of the davit.

25 6. A device for rendering the outboard side of a boat accessible when the boat is in inboard position on a vessel, constructed as set forth in claim 1, and wherein the lowering and raising means comprises a davit including a standard and an overhanging portion, means for mounting the standard on the vessel for rotation about a substantially vertical axis, and block and falls tackle assembled with the overhanging portion of the davit.

ALBERT C. PERRY.
